UNITED STATES PATENT OFFICE.

JAMES D. GABLER, OF NEW YORK, N. Y.

DESIGN FOR A PICTURE MAT.

Application filed March 13, 1919. Serial No. 282,517. Term of patent 3½ years.

To all whom it may concern:

Be it known that I, JAMES D. GABLER, a citizen of the United States, residing at New York city, in the county of New York, and State of New York, have invented a new, original, and ornamental Design for a Picture Mat, of which the following is a specification, reference being had to the accompanying drawing, forming part thereof.

The figure is a plane view of a picture mat, showing my new design.

I claim:

The ornamental design for a picture mat, as shown.

In testimony whereof I have signed my name to this specification.

JAMES D. GABLER.
